UNITED STATES PATENT OFFICE.

ALBERT F. SCHIERBURG, OF DENVER, COLORADO.

AMUSEMENT DEVICE.

Application filed August 26, 1927. Serial No. 215,632.

This invention relates to improvements in amusement devices of the type used at pleasure resorts and which are so constructed that their operation is dependent on the skill of the player.

It is quite common to have amusement devices that present a moving object which serves as a target for balls thrown by the players. If a player hits one or more of these targets by throwing a given number of balls, he is given a prize.

It is the object of this invention to produce an improved device of this type which shall be provided with three moving targets that pass in succession by an opening. In my present embodiment these targets are so made that they represent the three letters W, I and N. The device is so constructed that the letters stand substantially vertical when they move past the opening but which will fall over into a substantially horizontal plane when hit by a ball. Means is also provided for closing an electric circuit when the letter falls into horizontal position and for lighting a lamp located in a compartment whose front wall has a closure provided with a translucent or transparent area shaped like the letter that controls the light. When all three targets are down, the three compartments will be illuminated and the word "WIN" will be displayed. If the player knocks down less than three targets, the word "WIN" will be incomplete; means is provided for retaining the lamps lighted as long as desired and for extinguishing the lamps at the end of each play.

The above and other objects that may appear when the description proceeds are attained by means of a construction and an arrangement of parts that will now be described in detail, reference for this purpose being had to the accompanying drawing in which the preferred embodiment has been shown and in which:

Fig. 1 is a horizontal section taken on line 1-1, Fig. 2;

Fig. 2 is a front elevation of the device with parts broken away to better disclose the construction;

Fig. 3 is a vertical section taken on line 3-3, Fig. 1;

Fig. 4 is a section taken on line 4-4, Fig. 3;

Fig. 5 is a section taken on line 5-5, Fig. 3; and

Fig. 6 is a wiring diagram.

In the drawing I have illustrated the preferred form of my invention which consists of a framework "A" that forms a support for the moving parts. As this framework is merely a support formed from angle irons, I will not describe the same in detail; but will merely identify such parts thereof as are necessary for the purpose of explaining my invention. Secured to the side members 5 and 6 of the frame are two transverse bars 7 and 8. Two short bars 9 and 10 are secured to the vertical side of the transverse angle 8 and two similar bars 9^a and 10^a are secured to the vertical side of angle 7. Horizontal angle irons 11 and 12 are secured to the vertical bars 9 and 10 and serve as supports for the bearings 13 and 14. A shaft 15 is journalled in the bearings 13 and a similar shaft 16 is journalled in bearings 14. Shaft 15 carries a sprocket wheel 17 and shaft 16 carries a corresponding sprocket wheel 18. In addition to the sprocket wheel 18, the shaft 16 carries a sprocket wheel 19 that is connected by means of a sprocket chain 20 with a smaller sprocket wheel 21 that is carried on the shaft 22. Shaft 22 also carries a belt wheel or pulley 23 to which the power for operating the device is transmitted by means of a belt which has not been shown. The shaft 22 is journalled in boxes 24 carried on two vertical angles 25 and 26 in the manner shown in Fig. 3. Supported from the framework are two spaced guides 27 and 28 which are formed from U-shaped steel bars whose channels 29 face each other in the manner shown in Fig. 3. These guides are secured to the framework by means of vertical bars 9 and 10 that are attached to the transverse bars 7 and 8 by means of brackets 31. A sprocket chain 32 encircles the two sprocket wheels 17 and 18. Attached to some of the links of this sprocket chain are brackets 33 which have lateral projecting sides 34 that engage in the channels of the guides in the manner shown in Fig. 3. These brackets have each an upwardly extending part 35 which is provided with spaced integral end portions 36 between which is pivotally mounted the hinged member 37, which carries the target 38. This target can be moved from the full line position shown in Fig. 3 to the dot and dash line position and will automatically resume the latter position when it is carried to the lower side of the assembly. This movement from

the horizontal to the vertical position is assisted by means of a guide rod 39. The apparatus is enclosed in a housing having a front wall 40 which has an opening 41 across which the targets 38 pass during the operation of the machine. When the machine is in operation, the target moves from right to left, Fig. 2, in the manner indicated by the arrow and on the lower side of the apparatus 10 targets move in the opposite direction. The player is given a certain number of balls and throws at the targets during the time they cross the opening 41. If his ball strikes the target, the latter will fall rearwardly into 15 the position shown in full lines in Fig. 3.

It is my intention to provide an electrical apparatus by means of which the player can illuminate some lamps located within compartments whose front surface is closed by 20 means of a member having translucent and opaque areas which form the letters W I N. This indicator has been illustrated in Fig. 2 where it is designated by numeral 42.

For the purpose of lighting the lamps 43 I have provided a contact mechanism consisting of three elongated contact members 44, 45 and 46. These members are supported by means of channel members 47 that are secured to the upper flange of the transverse 30 angles 7 and 8 and are insulated from the latter by means of pieces of insulation 48. Each of the elongated contacts carries a downwardly projecting bolt 49 that extends through holes in the flanges of the channel 35 members 47 and through registering openings in the angles 7 and 8 in the manner shown in Fig. 4. The bolts 49 are also insulated from the members 7 and 8 by the same insulating member that serves to insulate the channels 47 from these transverse 40 angles. Each of the targets carry a contact 50 that is so located that it will engage one of the elongated contact members whenever the target is thrown into the horizontal 45 position shown in Fig. 3. Whenever a target is struck by the ball, it will fall rearwardly and the contact 50 will engage the elongated contact which will serve as a stop, the springs 51 serving as buffers so as to cushion 50 the impact of the target. By referring to Fig. 6 it will be observed that I have provided a source of electric energy which has been shown as a battery that has been indicated by reference numeral 52. A wire 53 55 extends from one pole of the battery to each of the lamps 43 in the indicator compartments 42. A wire 54 extends from the other terminal of each lamp to one of the bolts 49, so that the lamp is electrically connected with one of the elongated contacts. Another 60 wire 55 extends from the other terminal of the electrical source to the framework of the apparatus and is consequently electrically connected with the targets and therefore 65 when one of the targets is struck by a ball

and thrown rearwardly until it rests upon one of the elongated contacts, an electric circuit will be established which will light the lamp 43 that corresponds to the target that was hit; for example, if the player hits the 70 target carrying the letter "W", the lamp within the compartment whose closure has the translucent portion representing letter "W" will be illuminated and this letter will therefore become visible. In order that this lamp shall remain illuminated until all three 75 of the targets have passed the opening I have provided a switch 56 for each of the lamps 43. The stationary contact 57 of each of these switches is connected by means of a wire 58 to one of the lamps 43 while the movable contact of the switch is connected by means of a wire 59 with the conductor 55 or with some portion of the framework to which this conductor is attached. The construction of this switch has been shown in Fig. 5 in which the movable switch member has been designated by reference numeral 56^a. This member is pivoted at 60 to a stationary switch contact 61 and is provided with an extension 62 that engages the switch base 63 and serves to limit the motion of the blade in one direction. A spring 64 has one end attached to the movable blade at 65 and the other attached to the switch base at 66. This spring is so arranged that when the blade is in the vertical position it will lie on one side of the pivot 60 and if the blade is moved counterclockwise so that its end contacts with the stationary switch contact 57, the spring will be on the other side of the pivot and will tend to hold the switch in closed position. The spring 64 will therefore exert a force tending to hold the switch open and after the switch has been moved to closed position will tend to hold it closed. Each of the targets 38 carry a bracket 67 100 that engages the upper end of the switch blade 56^a and moves it towards closed position at the time that the contacts 50 leave the elongated contacts and therefore the lamps 43 will remain illuminated after the targets have passed from the horizontal position shown in Fig. 1 to the vertical position in which they extend downwardly in the manner indicated in the same figure. After the player has thrown all his balls, the operator can move the switch to open position by the simple expedient of applying pressure to the pedal 68 whose free end is connected by means of a rod 69 with the outer arm 70 of a lever that is pivoted at 61 and which has an arm 71 whose free end 72 is bent at right angles so as to extend transversely of the switch blades and which will engage all of the switch blades at one time. Whenever the operator moves the pedal 68, he can therefore disconnect such of the switches as have been closed by the targets. 110

The targets are formed from a steel plate 130

38 and have their front surfaces covered by means of a layer of felt 73 which is held in place by means of a layer of canvas 74. The letters that are represented by the targets 5 gets are painted on the outer side of the canvas 74. The object of padding the targets is to reduce the noise due to the impact of the ball which is used in playing the game. When this game is played an electric 10 motor or other power device is connected to the same by means of a belt which engages the wheel 23. This motor rotates the shafts 15 and 16 and moves the sprocket chain which carries the targets. The targets will 15 therefore pass across the opening 41 and during the passage of these targets the player throws a ball which, if it strikes the target, will knock it over into the position shown in Fig. 3. If the target is struck it 20 will light a lamp in one of the compartments of the indicator 42 and if the player hits all of the targets, the three letters W I N will be illuminated, thus indicating that the player won. If the player, however, fails to 25 knock over one of the targets, the word "WIN" will be incomplete and the player will therefore lose. It is apparent that a skillful player may be able to strike each one of the targets with the balls allotted to 30 him and therefore win; whereas a less skillful player will miss one or all of the targets so that this game is strictly a game of skill and not of chance.

From the above it will be apparent that 35 I have produced an amusement device which is of very simple construction and which is designed to attract the attention of the visitors at the amusement concessions and which indicates in illuminated letters whether the 40 player won or lost and which, in addition, has means for quickly clearing the indicator signals at the end of each game.

Having described my invention what I 45 claim as new is:

1. An amusement device comprising a plurality of targets, each representing a letter forming a word, means for normally supporting said targets in vertical position, said means permitting the targets to be moved 50 into horizontal position, means for moving said targets, a plurality of compartments each containing a lamp, each compartment having a cover having opaque and transparent areas that co-operate to display a letter when the lamp is lighted, and means 55 whereby each of the targets will light a lamp in one of the compartments whenever it is moved from vertical to horizontal position.

2. An amusement device comprising a 60 plurality of targets, each representing a letter forming a word, means for normally supporting said targets in vertical position, said means permitting the targets to be moved into horizontal position, means for 65 moving said targets, a plurality of compart-

ments, each containing a lamp, each compartment having a cover having opaque and transparent areas that cooperate to display a letter when the lamp is lighted, an elongated spring supported contact for each target, means for making electrical connection between one of said contacts and one of the targets when the latter is in horizontal position, a source of electric energy having one pole connected with the elongated contact 70 and the target when the latter is in horizontal position, one of said lamps being connected in series with said source of energy and each target and means comprising a switch for closing the electric circuit to each 75 of said lamps.

3. An amusement device comprising, in combination, a plurality of compartments placed side by side, each compartment having a lamp located therein, one side of each compartment being closed by a closure member having a transparent area outlining a letter whereby said letter will become visible when the lamp is lighted, an endless chain, means for moving said chain, a plurality of targets pivotally secured to the chain, means for holding said targets pivotally secured to the chain, means for holding said targets in substantially vertical position, said securing means also permitting the targets to be moved to horizontal position, a source of electric current, means for connecting one of said lamps in series with the source of electric current whenever one 90 of the targets is moved from vertical to horizontal position and manually operable means for breaking said connection.

4. An amusement device comprising, in combination, a plurality of compartments placed side by side, each compartment having a lamp located therein, one side of each compartment being closed by a closure member having a transparent area outlining a letter whereby said letter will become visible when the lamp is lighted, an endless chain, means for moving said chain, a plurality of targets pivotally secured to the chain, means for holding said targets in substantially vertical position, said securing means also permitting the targets to be moved to horizontal position, a source of electric current, means for connecting one of said lamps in series with the source of electric current whenever one of the targets is moved from vertical to horizontal position, 100 said means comprising an elongated contact for each target, a switch for each target and means carried by said targets for closing the switches.

5. An amusement device comprising, in combination, a plurality of compartments placed side by side, each compartment having a lamp located therein, one side of each compartment being closed by a closure member having a transparent area outlining a 115

letter whereby said letter will become visible when the lamp is lighted, an endless chain, means for moving said chain, a plurality of targets pivotally secured to the chain, means for holding said targets in substantially vertical position, said securing means also permitting the targets to be moved to horizontal position, a source of electric current, means for connecting one of said lamps in series with the source of electric current whenever one of the targets is moved from vertical to horizontal position, said means comprising an elongated contact for each target, a switch for each target, means carried by said targets for closing the switches and manually operable means for opening the switches.

6. An amusement device comprising, in combination, a supporting framework, means carried by the framework for supporting two sprocket wheels in aligned par-

allel relation, two endless guideways supported by the framework, one on each side of the wheel, a sprocket chain enclosing said wheels, means for rotating one of said wheels, a plurality of supporting brackets secured to the chain, said brackets having projecting portions that engage the guideways, a target pivoted to each bracket, a stop for limiting the movement of the target in one direction, a plurality of elongated contacts extending parallel with the plane of the sprocket wheels, a contact member carried by each, said contacts being so located that they will each engage a separate elongated contact, a switch corresponding to each of the elongated contacts, means carried by the targets for closing the switches and manually operated means for opening the switches.

In testimony whereof I affix my signature.

ALBERT F. SCHIERBURG.
